UNITED STATES PATENT OFFICE.

CHARLES S. MOTT, OF PATCHOGUE, ASSIGNOR OF ONE-HALF TO GEORGE H. SHAFFER, OF BROOKLYN, NEW YORK.

MAST-HOOP.

SPECIFICATION forming part of Letters Patent No. 453,585, dated June 2, 1891.

Application filed February 18, 1891. Serial No. 381,948. (No model.)

To all whom it may concern:

Be it known that I, CHARLES S. MOTT, of Patchogue, in the county of Suffolk and State of New York, have invented a new and useful Improvement in Mast-Hoops, of which the following is a full, clear, and exact description.

My invention relates to an improvement in mast-hoops, and has for its object to provide a sectional hoop capable of being readily sprung around a mast and the ends of the hoop securely fastened when said hoop is in position upon the mast.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a plan view of the hoop, having its ends united. Fig. 2 is a side view of the hoop, illustrating the means of connecting the ends. Figs. 3 and 4 are perspective views of the ends of the hoop, and Fig. 5 is a perspective view of the locking-sleeve.

The hoop 10 is constructed, preferably, of a tough wood—such as ash, oak, or hickory—and the hoop is made with two abutting ends 11 and 12. The end 11 is formed with a central tongue 13 of dovetail shape, the end face of which tongue is beveled inward, as shown at 14. In the end 12 a dovetail recess 15 is produced, practically corresponding in length and breadth to the equivalent measurements of the tongue, the said recess 15 being adapted to receive the tongue 13. The end wall of the recess 15 is inwardly and downwardly beveled to receive the beveled face of the tongue. A semicircular sleeve 16 is adapted to slide upon the hoop, and the said sleeve is usually provided at one or both ends with an aperture 17.

In operation, when a hoop is to be applied to a mast, the sleeve 16 is slid from over the united ends, and the tongue 13 is forced from the recess 15. The ends of the hoop are then bent or carried in opposite directions a sufficient distance to enable the hoop to be readily sprung around the mast. When this has been effected, the tongue is again entered into the recess 15 and the sleeve is slid over the joint and securely held in such position by a screw or equivalent device, which is entered into the sleeve at the aperture or apertures 17.

It is obvious that the hoop may in like manner be expeditiously and conveniently disengaged from the mast. The connections at the ends of the hoop are exceedingly simple, and when such connections are made the sleeve will remain permanently in position or until purposely disturbed.

Having thus described my invention, I claim as new and desire to secure by Letters Patent—

1. As an improved article of manufacture, a mast-hoop constructed with two abutting ends, one of which is provided with a dovetail tongue and the other with a dovetail recess to receive the tongue, and a sliding sleeve adapted to cover the connected ends of the hoop, as and for the purpose specified.

2. The combination, with a mast-hoop constructed with two abutting ends, one of which ends is provided with a dovetail tongue having a beveled outer end face, and the other end provided with a recess adapted to receive the tongue, of a sleeve held to slide upon the hoop and means, substantially as described, for locking the sleeve over the joint of the hoop, as and for the purpose specified.

CHARLES S. MOTT.
